CHARLES ROCKWELL CLARK, OF PLAINVILLE, CONNECTICUT.

WIND-SHIELD.

1,093,974.

Specification of Letters Patent. Patented Apr. 21, 1914.

Application filed February 24, 1913. Serial No. 750,087.

To all whom it may concern:

Be it known that I, CHARLES R. CLARK, a citizen of the United States of America, and residing at Plainville, in the county of 5 Hartford and State of Connecticut, have invented new and useful Improvements in Wind-Shields, of which the following is a specification.

The object of my invention is to provide 10 a wind shield for automobiles and the like vehicles which will effectively protect the occupants of the rear seat of the vehicle and which will not be in the way at any time.

My invention accordingly consists in 15 mounting the support for the shield upon the seat of the vehicle at a point in between the back cushion and the edge of the seat cushion, where it will be at the side of and out of the way of the person occupying the seat, and in securing the shield member upon this support in such a way that it may be set in any desired angular relation and held in such position.

Another feature of the invention resides 25 in the use of a supporting bracket which is fixedly secured to the seat or other part of the body, and a post which carries the shield proper and is detachably connected to the bracket, so that by these means the 30 shield may be readily mounted and unmounted, as desired.

Another feature consists in supporting the shield member at a point intermediate its ends with such point of support nearer the 35 rear end than to the front end so that the greater part of the shield member will extend forwardly of the support.

A further novel feature is a method of 40 mounting the shield member which consists in holding it in between pairs of inwardly extending clamping fingers of a supporting frame, the frame being cut away at points between the fingers of a pair, to render such finger more or less springy for 45 the purpose of yieldingly gripping the edges of the shield.

Another feature of the invention is a special form of clamp for detachably securing the shield-carrying post upon the supporting bracket and still another feature is a special holding device for securing the shield in any angular relation to which it may be adjusted.

Various other features will appear as the 55 specification proceeds.

In the accompanying drawings I have

illustrated my invention in a concrete and preferred form but I would have it understood that various changes and modifications may be made therein without departing 60 from the true scope and spirit of the invention.

Figure 1, is a longitudinal sectional view illustrating the application of my invention to an automobile, and showing two different 65 positions of the wind shield. Fig. 2, is a plan view. Fig. 3, is an enlarged broken view partly in section of the shield supporting means. Fig. 4, is a detached perspective view of the supporting bracket and 70 the clamping member for detachably securing the post upon this bracket. Fig. 5, is a sectional view of the frame which carries the shield proper, this view being taken substantially on the line 5—5 of Fig. 1. 75

The shield proper is designated 10. This is preferably transparent and is therefore usually in the form of a flat piece of comparatively heavy plate glass. The shape of the shield may vary but it is preferably 80 made longer than it is wide, substantially in the proportions shown. The shield is supported so as to lie substantially in front of the face of the occupant of the rear seat of the vehicle and is made angularly adjustable 85 so that the occupant may turn it to shield himself to best advantage. And in order that the supporting means for the shield shall not interfere with the usual and ordinary occupancy of the seat it is preferably 90 secured to the seat and disposed in between the back cushion and the edge of the seat cushion.

In Figs. 1 and 2 I have illustrated two preferred arrangements of the shield, the 95 numeral 11 there indicating the rear seat of the car, 12 the back cushion, and 13 the seat cushion. The preferred form of supporting means is also shown in this view, it consisting essentially of a supporting bracket 14 100 which is secured fast to the seat, and a shield-carrying post 15 which is detachably secured to the bracket. The upstanding supporting bracket is preferably made in one piece with a wide flat base 16 secured to 105 the seat with screws 17 or like fastenings and with a downturned hooked portion 18 on its upper end. Also the upstanding portion of the bracket is preferably inclined more or less as indicated at 19 to fit in 110 closely against the base of the back or arm cushion so as not to interfere with the seat

- cushion being pushed all the way back to where it belongs.
- The post 15 is preferably in the form of a hollow column and it is secured to the bracket preferably by means of a clutch member which engages the hook 18 on the bracket. To afford a firm seat for the post upon the bracket, the post is preferably provided with a foot or base 22 having a ledge 23 resting on top of the bracket and a part 24 extending downwardly into engagement with one side of the bracket and the clutch member 21 is made with a flat toe portion 25 engaging the opposite side of the bracket.
- 10 To secure a wedging engagement between the clutch member and the hook on the bracket, the clutch member 21 is preferably made with an inclined wedging surface 26 which engages directly with the point of the hook. The clutch member is in the case illustrated operated by a nut 27, in the upper end of the post, which engages with a screw rod 28 connected at the lower end to the clutch member. The screw rod is shown 20 fixedly connected to the clutch member by means of a transverse key or pin 29, which engages the head portion 30 of such member, this head portion being received in a suitable recess 31 provided for that purpose 25 in the base of the post.
- The preferred form of adjustable mounting for the shield member is best illustrated in Fig. 3, wherein the post is shown as carrying a head 32 on its upper end in which 30 is seated a spindle 33, which carries the shield. This so-called head is made with a socket 34 to receive the spindle and above this socket it is made with a concentric enlargement of seat 35 to receive a corresponding 35 enlargement or hub 36 on the spindle. This enlarged shouldered portion of the spindle is provided with a series of peripherally arranged vertical slots 37 therein which are arranged to be engaged by a dog 38, pivoted at 39 on the head. The head is provided with a slot 40 opening into the seat 35 to permit passage of the dog into engagement with the hub inclosed within such seat. The nose or point of the dog is preferably disposed on an arc of a circle as indicated at 41 and the slots in the spindle may be correspondingly curved. Also that part between the bearing lugs 42 in which the dog is pivoted is cut away as at 43 to receive 45 the point of the dog when the dog is tilted down to the dotted line position (Fig. 3). In this position the nose of the dog is free of the slots in the spindle and the shield may therefore be turned to any desired angle. As soon as released the dog will fall by reason of the weight of its operating handle 60 so as to automatically lock the shield in the position to which it has been turned. Disengagement of the spindle from 50 its socket may be prevented by the use of a lock screw 44, the point of which engages in an annular groove 45 in the spindle.
- The head in which the spindle is mounted may also carry the nut by which the clutch member is operated. Thus in Fig. 3 the nut is shown forming an integral part of the head, it being connected thereto by arms 46. The nut is thus in this case merely a screw threaded seat in the lower end of the revolute head. To serve the function of a nut the head makes abutting engagement with the upper end of the hollow post at the point 47 and the joint at this point may be concealed by providing the head with a downwardly extending flange 48. The head may be turned to adjust the clutch member by any suitable means. It is in the illustration shown provided with an opening 49 to receive the point of a spanner wrench. The head may also be turned by means of the handle 60 when the dog 38 is disengaged from the slots 37.
- The shield is preferably mounted in a frame 50 which may be secured to the head of the spindle by engaging it between two upstanding ears 51 on the top of the spindle. The preferred manner of securing the shield in this frame is to grip it between pairs of spring clamping fingers or lugs 52. Sufficient flexibility may be given these fingers 55 by cutting away the material of the frame between each pair of such lugs, substantially as indicated at 53. Screws 54 or like fastening means may be employed for drawing the lugs together into clamping engagement with the shield held therebetween. Pads 55 of felt or like material may be interposed between the lugs and the shield material and shoulders 56 are preferably provided at the lugs to limit the inward movement of the shield in between the lugs and to hold the shield free of engagement with the frame at all points except at the lugs. This structure provides an extremely ornamental mounting for the shield and at the same time renders the replacement of the shield a very easy matter. Additional lugs 61 may be provided for holding the shield at the corners of the frame.
- To get the greatest range of usefulness 115 the shield should extend forwardly from its support a considerable distance. I therefore prefer to support the same at a point in between its ends but nearer to the rearward end. In this way the greater portion 120 of the shield lies forward of the support so that by adjusting it angularly about the support the wind coming from practically any direction may be warded off.
- It will be noted that the supporting 125 bracket is preferably made quite broad, as shown in Fig. 4. This gives the strength and rigidity required, provides a wide and firm gripping joint between the bracket and post and at the same time allows for a cer-

tain range of lateral adjustment of the post upon the bracket. This lateral adjustment adds further to the efficiency of the shield because if the desired shielding effect cannot be obtained by a simple angular adjustment of the shield, then the shield may be shifted bodily in either direction until just the right effect is secured.

While I have so far found it desirable to locate the shield carrying support at the end of the seat, I would have it understood that it may be located at other points, as may be found most suitable. Thus it might be located at the rear of the seat, in which case it would be disposed between the rear edge of the seat cushion and the back cushion. Both these possible arrangements are clearly illustrated in Figs. 1 and 2, the shield at the right in Fig. 2 and shown in detail in Fig. 20 1 being disposed at the rear edge of the seat with its supporting bracket engaged in between the rear edge of the seat cushion and the back cushion, while the shield shown at the left in Fig. 2 is disposed at the end of the seat and with its supporting bracket interposed in between the end edge of the seat cushion and the back cushion which at that point forms the arm rest and constitutes the end of the seat. This latter is the preferred 30 arrangement because it provides a greater possible range of adjustment of the shield. Another advantage of this arrangement is that the bracket, lying as it does between the end of the seat cushion and the arm rest is disposed longitudinally of the car and therefore when the clamp is loosened the whole shield may be adjusted either forwardly or rearwardly. I have used the term back cushion as a convenient expression for designating the upright cushion lying at the rear and ends of the seat for providing the back rest and arm supports and the expression will therefore be construed in the broadest sense in which it is used.

45 What I claim is:—

1. In a vehicle, a seat having a back and side arms, upright cushions for the back and side arms extending downward substantially to the seat and a seat cushion resting on the 50 seat with its edges fitting closely against the lower edge of the upright cushions, a supporting bracket secured to the seat beneath the seat cushion and adjacent to one of the upright cushions, a post carried by said bracket disposed between said upright cushion and the edge of the seat cushion, extending upwardly above the seat cushion and lying relatively close against said upright cushion to be thereby out of the way of the 55 occupant of the seat, an angularly adjustable transparent wind shield mounted on the post and conveniently accessible means for securing the wind shield in different angular adjustments.
- 60 2. In an automobile wind shield, the combination of a supporting bracket arranged for attachment to the body portion of an automobile and provided with a hook on its upper end, a post resting upon the hooked upper end of the bracket and provided with a downwardly extending part engaging the side of the bracket, a dependent clutch member carried by the post, engaging the opposite side of the bracket and making wedging engagement beneath the hook on the 70 bracket, means for drawing the clutch member into firm engagement with the hook whereby to clamp the post upon the bracket and a wind shield mounted upon the upper end of the post.

3. In an automobile wind shield, the combination of an upstanding supporting bracket arranged for attachment to the body portion of an automobile and provided with a hook on its upper end, a hollow post resting upon the hooked upper end of the bracket and provided with a downwardly extending part engaging one side of the bracket, a dependent clutch member carried by the post, engaging the opposite side of the bracket and making wedging engagement beneath the hook on the bracket, means for drawing the clutch member into firm engagement with the hook whereby to clamp the post upon the bracket and a wind shield mounted upon the upper end of the post.

3. In an automobile wind shield, the combination of an upstanding supporting bracket arranged for attachment to the body portion of an automobile and provided with a hook on its upper end, a hollow post resting upon the hooked upper end of the bracket and provided with a downwardly extending part engaging one side of the bracket, a dependent clutch member carried by the post, engaging the opposite side of the bracket and making wedging engagement beneath the hook on the bracket, a screw rod fixed to the clutch member and extending up through the hollow post, a rotatable head seated in the upper end of the post, making abutting engagement with the end of the post and provided with a screw threaded seat receiving the threaded end of the rod and a shield member mounted on the head.

4. In an automobile wind shield, the combination of a one-piece supporting bracket made with a broad flat base, an upright portion bent up from the base and a hook turned down at the upper edge of such upright portion, a post resting upon the upper edge of the bracket and having a backing part, an adjustable clamping hook carried by the post and engaging beneath the hook on the supporting bracket opposite said backing part, a shield carrying member rotatably adjustable on the post and means for securing said member in adjusted position upon the post.

5. In an automobile wind shield, the combination of a support having a flat base secured to the seat of the automobile and an upright portion extending up between the back cushion and the edge of the seat cushion, said upright portion being inclined at its lower end to substantially fit the inclination of the lower end of the back cushion, so as not to interfere with the seat cushion being pushed back into proper engagement with the back cushion, an angularly adjustable shield member mounted upon the support and means for securing said shield member in its adjusted position.

6. In an automobile wind shield, the combination of a supporting post, a head on

the upper end of the post provided with a shouldered seat having an opening in one side thereof, a spindle rotatably engaged in said seat and provided with a peripheral series of slots therein, a shield member carried by said spindle and a pivoted dog carried by the post having a part arranged to project through the opening in the side of the seat into engagement with any one of 10 the peripheral slots in the spindle for locking the same.

7. In an automobile wind shield, the combination of a supporting post, a head on the upper end of the post provided with a shouldered seat having an opening in one side thereof and with a spindle socket below the seat, a rotatable spindle engaged in the socket, provided with a shouldered enlargement engaged in the seat aforesaid and 20 having a peripheral series of slots therein, a dog pivoted on the head arranged in one position to project through the opening in the seat into engagement with one of the slots in the enlargement on the spindle and 25 a shield member carried by the spindle.

8. In an automobile wind shield, the combination of a hollow post, a head rotatably seated in the post in abutting engagement with the upper end thereof, a screw-threaded seat in the lower portion of the head, a screw rod passing up through the post and engaged in said seat, a supporting bracket, a clutch member connected with the lower

end of the screw rod and engaging the supporting bracket whereby to secure the post upon such bracket, a spindle rotatably seated in the head and provided with a peripherally slotted portion also received within the head, a pivoted dog on the head arranged to project inwardly into engagement with the slots in the spindle, and a shield member carried by the spindle.

9. An automobile wind shield comprising a supporting bracket, a hollow post engaged with said bracket, a member carried by the post, arranged for clamping engagement with the bracket, a connection from said clamping member extending up through the hollow post, means mounted in the top of the post engaging the said connection for operating the clamping member, a shield member rotatably mounted on the post and means also mounted at the top of the post for securing the shield member in adjusted position thereon.

10. In a vehicle having front and rear seats, the rear seat having a back and side arms with cushions, a transparent wind shield, a post for supporting said shield and a base bracket for said post secured to the rear seat beneath its cushion.

CHAS. ROCKWELL CLARK.
